[57] CLAIM

The ornamental design for a resectoscope electrode, as shown and described.

DESCRIPTION

FIG. 1 is a perspective view of a resectoscope electrode, showing our new design;

FIG. 2 is a top plan view thereof;

FIG. 3 is a side elevational view thereof, the opposite side being identical thereto;

FIG. 4 is a bottom plan view thereof;

FIG. 5 is a front elevational view thereof; and

FIG. 6 is a rear elevational view thereof.

The broken lines showing of the electrode tip is for illustrative purposes only and forms no part of the claimed design.

FIG. 1.FIG. 2.FIG. 3.FIG. 4.FIG. 5.FIG. 6.
